UNITED STATES PATENT OFFICE.

HENRY A. DUPIECH, OF ST. LOUIS, MISSOURI.

DESIGN FOR A BOTTLE.

Application filed May 11, 1928. Serial No. 26,627. Term of patent 7 years.

To all whom it may concern:

Be it known that I, HENRY A. DUPIECH, a citizen of the United States, residing at 2044 Ann Ave., city of St. Louis, and State of Missouri, have invented a new, original, and ornamental Design for Bottles, of which the following is a specification, reference being had to the accompanying drawing, forming part thereof.

The figure is a side view in elevation of a bottle, showing my new design.

I claim:

The ornamental design for a bottle, as shown.

HENRY A. DUPIECH.
